United States Patent Office

Des. 196,001
Patented Aug. 13, 1963

196,001

JUG

Walter Zaleski, Freehold, N.J., assignor to Hyspec Container Corporation, Keyport, N.J., a corporation of New Jersey

Filed Aug. 17, 1962, Ser. No. 71,338

Term of patent 14 years

(Cl. D58—5)

FIG. 1

FIG. 2

FIG. 3

FIGURE 1 is a top plan view of a jug embodying my new design;

FIGURE 2 is a side elevational view thereof, showing parts broken away for the purpose of illustrating indeterminate length.

FIG. 3 is a cross-sectional view taken along line 3—3 of FIG. 2.

The dominant features of my design reside in the portions shown in full lines.

I claim:

The ornamental design for a jug, as shown and described.
